UNITED STATES PATENT OFFICE.

BUEL COUCH, OF SIOUX CITY, IOWA.

BINDER.

1,097,391.

Specification of Letters Patent.

Patented May 19, 1914.

Application filed February 7, 1913. Serial No. 746,912.

To all whom it may concern:

Be it known that I, BUEL COUCH, a citizen of the United States, residing at Sioux City, in the county of Woodbury and State 5 of Iowa, have invented certain new and useful Improvements in Binders; and I do hereby declare the following to be a full, clear, and exact description of the invention, such as will enable others skilled in the art 10 to which it appertains to make and use the same.

This invention relates to paper binders and has for an object to provide a binder with improved means for maintaining the 15 engaging wires in engaging position.

A further object of the invention is to provide improved means for operating and locking the engaging wires.

A further object of the invention is to 20 provide hinge engaging wires with improved means for moving the wires upon their hinges and locking them in engaging position.

With these and other objects in view the 25 invention comprises certain novel constructions, combinations and arrangement of parts as will be hereinafter more fully described and claimed.

In the drawings: Figure 1 is a view of the 30 improved binder shown in perspective and in engagement with a conventional book cover. Fig. 2 is a plan view of the binder with the cover member removed showing the operating parts. Fig. 3 is a sectional view 35 showing one of the wire sections with its hinge and foot member taken on line 3—3 of Fig. 2. Fig. 4 is a detail sectional view showing one of the operating cams in side elevation. Fig. 5 is a transverse sectional 40 view taken on line 5—5 of Fig. 2 and showing the lock in section. Fig. 6 is a detail perspective view of a fragment of one of the 45 hinge wires and the foot. Fig. 7 is a fragmentary view in side elevation of the locking wire.

Like characters of reference designate corresponding parts throughout the several views.

The improved binder which forms the 50 subject matter of this application includes a base or back 10 preferably constructed of channel metal and adapted to be secured in the back of a book shown at 11. Disposed adjacent the ends of the channel 10 are blocks 12 and 13 in one side of which are rigidly mounted engaging wires 14 extend-

ing upwardly above the channel back 10 and curved as at 15. At the other end of the blocks 12 and 13 foot blocks 16 and 17 are pivoted in slots in the blocks 12 and 13 as at 60 18 and 19. The foot blocks 16 and 17 carry engaging wires 20 which are formed at their upper ends with curves 21 whose extremities are shaped to properly engage and interlock with the extremities of the wires 14 in 65 the usual well known manner. Under the foot blocks 16 and 17 springs 22 are employed which serve to yieldingly hold the wires 20 outwardly away from the wires 14 as shown at Fig. 3 and in dotted lines at 70 Figs. 1 and 2.

To move the wires 20 into engagement with the wires 14 and lock them in such position a cam 23 is provided bearing in a depression 24 in the toe 16' of the foot block 75 16 and a similar cam 25 bearing in a depression 26 in the toe 17' of the foot block 17. The cams 23 and 25 run through slots 27 in the blocks 12 and 13 so that when the cams are moved longitudinally they serve to force 80 the foot blocks 16 and 17 downwardly around their pivots against the tension of the springs 22 and to close the wires 20 into locking engagement with the wires 14, as shown at Fig. 1. To move said cams the 85 same are formed upon the extremities of a wire or rod 28 having a return bend at 29 at one end as indicated at Figs. 1, 2 and 7 which bend is turned upwardly as indicated at Figs. 1 and 7 to form a hand hold. 90

The wire 28 is provided with a notch 30 which passes under a keeper 31 carried upon the channel back 10 so that when moved forward to locking position the resiliency of the wire 28 serves to spring such wire upwardly until the keeper 31 is seated in the notch 30 and prevents accidental unlocking of the parts. It will be apparent that simply longitudinal sliding of the wire 28 carrying the cams 23 and 25 serves to oscillate the wires 20 upon their pivots from full line to dotted line position, as shown at Fig. 1 and that when the wire is moved to locking position it is itself locked by the keeper 31 to maintain the extremities of the wires 14 and 20 in engagement and to maintain the sheets indicated at 32 properly upon such engaging wires. A cover member 33 is also provided having openings 34 which pass over the wires 14 and slots 35 which 105 permit the movements of the wires 20 upon their pivots, such cover being employed 110

2
simply to close the channel member and cover the operating parts.

I claim:—

1. In a binder, a channel back, rigid blocks along the same, and rigid wires rising from such blocks, combined with foot blocks pivoted along the back and having toes extending inward toward the rigid wires, wires rising from the foot blocks and coating at their upper ends with the rigid wires, springs throwing the toes normally upward, and a rod movable longitudinally in the back and having cams overlying said toes, for the purpose set forth.
- 15 2. In a binder, a back, foot blocks pivoted upon the back, rigid engaging wires extending from the back adjacent said blocks, wires carried by the foot blocks and extending in normal parallelism with the rigid wires, the ends of said wires being curved to engage each other, coil springs respectively disposed between the foot blocks and back for normally holding the blocks and back for normally holding the wires in spaced relation, and manually controlled means coöperating with said foot blocks to simultaneously swing the latter against the tension of the springs to engage said wires.
- 30 3. In a binder, a back, rigid wires extending from the back, foot blocks pivoted upon the back adjacent the rigid wires, wires carried by the foot blocks and extending in normal parallelism with the rigid wires, the extremities of said wires being curved to engage each other, a rod extending longitudinally of the back and in parallelism with the pivots of the foot blocks, and cams carried by the rod bearing upon and adapted to oscillate the foot blocks and wires carried thereby.
- 35 4. In a binder, a back, rigid blocks along the same having transverse slots, and rigid wires rising from said blocks; combined with foot blocks pivoted to said rigid blocks and having toes with depressions in their upper edges, wires rising from the foot blocks and coating with the other wires, springs throwing said toes normally upward, a rod movable longitudinally in the back and having cams sliding in said slots and depressions, and means for holding the rod at one extreme position.
- 45 5. In a binder, a back, rigid blocks along the same having transverse slots, and rigid wires rising from said blocks; combined with foot blocks pivoted to said rigid blocks and having toes with depressions in their upper edges, wires rising from the foot blocks and coating with the other wires, springs throwing said toes normally upward, a rod movable longitudinally in the back and having cams sliding in said slots and depressions, the rod having a handle at one end and a notch adjacent said handle, and a keeper on the back engaging said notch at one extreme position of the rod.
- 55 6. In a binder, a channel back, rigid blocks along the same, and rigid wires rising from such blocks; combined with foot blocks pivoted to the rigid blocks and having toes 60 extending inward toward them, wires rising from the foot blocks and coating at their upper ends with the rigid wires, springs throwing said toes normally upward, a rod movable longitudinally in the back and having cams overlying said toes for the purpose set forth, the rod having a handle at one end and a notch adjacent said handle, and a keeper on the back engaging said notch at one extreme position of the rod.
- 65 7. In testimony whereof I affix my signature in presence of two witnesses.

BUEL COUCH.
